United States Patent Office

Des. 208,283
Patented Aug. 8, 1967

208,283

ROTARY RACK UNIT FOR MEDICAL EQUIPMENT

General L. Cranfill, Friona, Tex., assignor to
Cranford Corporation, Dallas, Tex.

Filed Mar. 11, 1965, Ser. No. 84,208

Term of patent 14 years

(Cl. D83—1)

FIG. 1

FIG. 2

FIG. 1 is a perspective view of the rotary rack unit for medical equipment showing my new design.

FIG. 2 is a side elevational view of the device shown in FIGURE 1.

I claim:

The ornamental design for a rotary rack unit for medical equipment, as shown.
